UNITED STATES PATENT OFFICE.

JOHN MARTINCSAK, OF NEW YORK, N. Y.

DESIGN FOR A BURIAL-CASKET.

44,769.

Specification for Design.

Patented Oct. 21, 1913.

Application filed August 5, 1913. Serial No. 783,198. Term of patent 14 years.

To all whom it may concern:

Be it known that I, JOHN MARTINCSAK, a citizen of the United States, and residing in the borough of Manhattan, in the county of New York, State of New York, have invented a new, original, and ornamental Design for a Burial-Casket, and of which the following is a specification, reference being had to the accompanying drawing, forming part thereof.

Figure 1 of the accompanying drawing is

a plan view of a burial casket showing my design; Fig. 2 a side view, and, Fig. 3 an end view looking at the smaller or foot end of the casket.

I claim;—

The ornamental design for a burial casket, as shown.

JOHN MARTINCSAK.
